FIG. 1.

FIG. 2.

FIG. 3.

HARRY M. DUNCAN INVENTOR.

BY

Hazard & Miller
ATTORNEYS.

UNITED STATES PATENT OFFICE.

HARRY M. DUNCAN, OF LOS ANGELES, CALIFORNIA.

REPRODUCER FOR PHONOGRAHS.

1,411,566.

Specification of Letters Patent. Patented Apr. 4, 1922.

Application filed February 3, 1921. Serial No. 442,184.

To all whom it may concern:

Be it known that I, HARRY M. DUNCAN, a citizen of the United States, residing at Los Angeles, in the county of Los Angeles and 5 State of California, have invented new and useful Improvements in Reproducers for Phonographs, of which the following is a specification.

It is the object of this invention to provide 10 a sound reproducer having extremely simple but efficient means for varying the intensity of the sound produced.

A reproducer constructed in accordance with the invention will also eliminate to a 15 great extent all scratching sounds incident to the employment of usual reproducers. Variations in the intensity of the sound and the elimination of scratching is produced by providing a spring loop in the stylus bar 20 and mounting a clamping member upon said spring loop for adjustment upon the same.

The invention will be readily understood from the following description of the accompanying drawings, in which

25 Figure 1 is a front elevation of a reproducer constructed in accordance with the invention.

Fig. 2 is a section through the same on the line 2—2 of Fig. 1.

30 Fig. 3 is a detail section on the line 3—3 of Fig. 1.

The reproducer in its general construction may be of standard design and is illustrated as including a casing 1 carrying a diaphragm 2 mounted between annular supporting rings 3. A usual sound opening 4 projects from the casing and is provided with a usual connection 5 by means of which the reproducer is mounted upon a tone arm.

35 The stylus bar 6 extends radially of diaphragm 2 in usual manner and is mounted upon a lug 7 projecting beyond casing 1 so that the stylus bar may be rocked slightly to move the end of the same overlying the 40 diaphragm toward and away from the diaphragm. The projecting end of the stylus bar is provided with a usual socket 8 adapted to receive a stylus 9 held in position by means of set screw 10.

45 In my improved reproducer the end of the stylus bar which overlies the diaphragm 2, instead of being directly secured thereto at the center of the diaphragm, is provided with a spring loop 12 projecting longitudinally beyond the stylus bar an appreciable 50 distance beyond the center of the diaphragm

and then being reversely bent, as shown at 12^a, with the end of said reversely bent portion secured to the center of the diaphragm, as shown at 13.

60 A clamping member is mounted upon the spring loop thus formed and is shown as comprising a casing 14 having the two arms of the loop received through the same with a block 15 interposed between the loop arms 65 and movably secured within casing 14 by means of a pin 16 extending through the block and having its ends received in longitudinal slots 17 provided in casing 14. A set screw 18 is threaded through casing 14 and 70 is adapted to impinge against one of the loop arms for clamping the loop arms to block 15 and to casing 14. By this arrangement it will be seen that the casing may be readily secured in adjusted positions back 75 and forth along the length of the spring loop.

When the casing is clamped to the loop adjacent the end of spring arm 12^a, which is connected to the diaphragm, a substantially rigid connection is provided between stylus bar 6 and the diaphragm by means of casing 14, but when the casing is fixed upon the spring loop adjacent its opposite end, as shown in dotted lines in Fig. 2, a 80 relatively resilient connection is formed between the stylus bar and the diaphragm, since the spring arms having the loop now form a part of the connection. As a consequence, it will be noted that the vibrations transmitted to the diaphragm from the stylus bar when the casing 14 is secured to the spring loop adjacent its outer end will be slight as compared with the vibrations transmitted to the diaphragm when 85 casing 14 is mounted upon the end of the spring loop which overlies the center of the diaphragm. The intensity of the tones reproduced will therefore be varied in accordance with the adjustment of casing 14 90 back and forth along the spring loop, and when the casing 14 is so adjusted as to form relatively slight vibrations the disagreeable scratching incident to the use of a usual sound reproducer will be eliminated. 95

100 The adjustment of casing 14 thus forms an extremely simple but accurate means for adjusting the intensity of sounds reproduced to any desired degree.

110 Various changes may be made without departing from the spirit of the invention as claimed.

What is claimed is:

1. A sound reproducer having a diaphragm, a stylus bar, a spring loop projecting from said bar and secured to said diaphragm, and a clamp mounted upon said spring loop and arranged for adjustment along the same.
- 5 2. A sound reproducer having a diaphragm, a stylus bar, a loop connecting said

bar and diaphragm, the ends of said loop connected respectively to said bar and diaphragm, a clamp mounted upon said loop and arranged for adjustment along the same.

In testimony whereof I have signed my name to this specification.

HARRY M. DUNCAN.
